UNITED STATES PATENT OFFICE

2,457,597

WATER HEATER

Clark M. Osterheld, Stoughton, Wis., assignor to
McGraw Electric Company, Elgin, Ill., a cor-
poration of Delaware

Application November 19, 1946, Serial No. 710,775

1 Claim. (Cl. 219—39)

1 My invention relates to electric heaters and particularly to water heaters of the internal type.

An object of my invention is to provide an internal water heater of a new and improved kind.

Another object of my invention is to provide a novel form of electric water heater in which insulation integral with the component parts thereof are provided.

Other objects of my invention will either be apparent from a description of several forms of device embodying my invention or will be set forth in the course of such description and be pointed out in the appended claim.

In the drawings,

Figure 1 is a view in vertical section through a domestic iron hot water tank having associated therewith an electric water heater embodying my invention.

Fig. 2 is a view in side elevation of my improved electric water heater with certain parts cut away to show the internal construction thereof.

Fig. 3 is a fragmentary view of a modification of electric heater embodying my invention.

Fig. 4 is a view in lateral section thereof taken on the line 4—4 of the Fig. 3, and,

Fig. 5 is a view in lateral section therethrough taken on the line 5—5 of Fig. 2.

Referring first of all to Fig. 1 of the drawings, I have there shown a standard domestic iron hot water tank 11 comprising a lower closure 13, having associated therewith a cold water inlet pipe 15 and an upper closure member 17 having associated therewith a hot water outlet pipe 19.

I provide also a mass 21 of electric insulating material which is held in proper operative position as by an outer casing 23.

I provide an internal water heater 25 which comprises a tubular member 27 which is shown as being substantially of square shape in cross section. Within tubular member 27 I provide a plurality of liners 29, four in number, and within the four liners 29 I provide four resistance conductors 31. Each resistance conductor comprises a plurality of transversely extending end-connected convolutions, these convolutions of strip, and while I may use a material for the conductors 31 substantially the same as is now used for resistance conductors I may also use aluminum.

I provide a terminal lead 33 for the inner end of each of the resistance conductors 31 and I provide a second terminal lead 35 for the outer end of each resistance conductor.

The wall thickness of tube 27 may be on the order of .035" in thickness although it may vary between the limits of .03" to .04", or even slightly

beyond these values. The thickness of the liners 29 and of additional liners 37, which liners 37 are used to space apart the individual resistance conductors 31 may be on the order of .015" and may vary between the limits of .01" to .02". The thickness of the conductor 31 and distance between adjacent convolutions may be determined by the amount of energy to be translated into heat in a heater of this kind and also by the length of the heater 25.

The entire outer surface of resistance conductor 31 is covered by an integral, inorganic, heat-conducting, high-temperature-resisting and electric-insulating coating having a thickness of the order of .001" although I desire it to be understood that the thickness of this coating may vary between the limits of .0005" and .0015". U. S. Patent #1,526,127 discloses one process for making such a coating. The liners 29 and 37 may have a thickness on the order of .015" and be also covered by a coating of the same kind and thickness as hereinbefore described for the resistance conductor 31.

The heater 25 is held in proper operative position and watertight engagement with tank 11 by a member 39 and by a washer 41, which washer 41 is provided with an inward extension 43 adapted to engage a washer of electric insulating material. A pair of bolts 45 with nuts 47 thereon hold the heater assembly in watertight engagement with tank 11. Member 39 is secured to the outer face of tank 11 by a welded seam.

I provide a plurality of sheaths 49 on the casing 27, these sheaths 49 being preferably of relatively thin aluminum, the thickness of this aluminum being variable between the limits of .015" to .035". Each sheath 49 is substantially channel shape in lateral section, with side portions 51 whereby it may be secured against the outer surface of one of the sides of tube 27 so that it may conduct heat from the resistors 31 to the water in the tank 11.

Referring now to Figs. 3 and 4 of the drawings, I have there shown a modification of an electric heater embodying my invention, this electric heater comprising a tube 55 which may be made of circular shape in cross section and which has positioned therein a liner 57 preferably of aluminum. The tube 55 may also be made of aluminum. Within tube 55 and liner 57 I position a resistance conductor 59 which comprises a strip of resistance material which is wound on edge in substantially helical form and which when placed in proper operative position within tube 55 will hold liner 57 tightly against the inner sur-

face of tube 55. The resistance conductor is preferably made of aluminum.

I provide a plurality of sheaths 61 which are preferably made of aluminum which is relatively thin, the wall thickness of sheath 61 being on the order of .015" to .035". Each of the hollow sheaths 61 is provided with side portions 63 which are adapted to be tightly secured against the outer surface of tube 55 so as to conduct heat generated within tube 55 away from the tube and into the water in tank 11.

The device embodying my invention thus provides a novel form of electric water heater which will not be too great to enable it to be installed in a tank 11 through a relatively small opening. The use of an integral, inorganic, electric-insulating coating of the relatively small thickness hereinbefore mentioned permits of making the heater of minimum dimensions and still obtain a relatively large amount of heat generated therein.

Various modifications may be made in the device embodying my invention without departing from the spirit and scope thereof, and I desire that all such modifications clearly coming within the scope of the appended claim shall be considered a part of my invention.

I claim as my invention:

An electric water heater for insertion into a hot water tank, comprising a relatively thin, 30

round, tubular, metallic casing having closed inner end, a thin metal liner covering substantially all of the inner surface of said casing, a metallic resistor strip helically wound on edge in said casing and inherently expanded to hold said liner in tight engagement with said casing and a heat-transmitting sheath on said casing forming with the external surface of said casing a series of longitudinal spaces, the inner surface of said casing, the entire surface of said liner and of said resistor strip having thereon an integral, inorganic, heat-conducting, high-temperature-resisting and electric-insulating coating.
